UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

NEEDLE-CLAMP.

1,401,466.

Specification of Letters Patent.

Patented Dec. 27, 1921.

Application filed May 11, 1918. Serial No. 234,007.

To all whom it may concern:

Be it known that I, ALBERT H. DE VOE, a citizen of the United States, residing at Westfield, in the county of Union and State 5 of New Jersey, have invented certain new and useful Improvements in Needle-Clamps, of which the following is a specification, reference being had therein to the accompanying drawings.

10 This invention relates to sewing machines and specifically to means for clamping needles to the needle-bar thereof.

In multiple needle machines using slabbed shank needles it has been customary to drill a 15 succession of parallel sockets as close together as possible and file away or otherwise remove, the intervening material to form an elongated opening with parallel sides and rounded ends. Such a type of needle-clamp necessitated the use of needles whose shanks 20 are slabbed differently. In renewing such needles vexatious delays often resulted. It is an object of the present invention to provide a needle-clamp whose socket is 25 fashioned to receive needles with shanks slabbed alike to avoid embarrassment and delay in replacing and renewing the same.

In the needle-clamps for multiple stitching machines of the type mentioned it is desirable 30 in some instances to form seams in close parallel rows. The present invention also aims to permit stitching in close parallel rows without sacrificing rigidity of grip on the needle or unduly weakening its 35 shank.

The invention consists of a needle-clamp secured to the lower end of a needle-bar and provided with a rectangular socket in 40 longitudinal alinement within which is a thrust or clamp-screw threaded into an end wall of the socket and adapted to grip the shanks of needles slabbed on opposite sides in parallelism.

A form of the invention is illustrated in 45 the accompanying drawings, in which Figure 1 is a front elevation of the clamp on the lower end of a needle-bar, a part thereof being shown in section. Fig. 2 is a transverse section through the clamp on 50 the line A—B, Fig. 1, and Fig. 3 is a perspective of the parts of the clamp in spaced relation.

The lower end of the needle-bar 1 is 55 drilled and tapped as indicated to receive the threaded shank 2 of a block 3 channelled at 4

transversely of the axis of the needle-bar and also longitudinally channelled on opposite sides parallel with the needle-bar as indicated at 5—5. Bands 6—6 provided with T-shaped channels 7—7 embrace the block 60 3 with their lugs 8 fitted snugly and tightly into the channels 5—5. Into one of the bands 6—6 is threaded a clamping screw 9 in line with the transverse channel 4. Needles 10 having their shanks slabbed in 65 parallelism, as indicated at 11, and all alike, are adapted to seat within the the rectangular socket formed by the channel 4 and bands 6—6 in which socket they may be clamped by the screw 9. The transverse 70 channel 4 in width is equal to the diameter of the needle-shanks, thus lining the needles up in one plane.

While it is preferred to removably secure the bands 6—6 by a snug fit of the lugs 8 75 within the channels 5, it is obvious that the securing of the bands 6 to the block 3 may be permanent and effected in other ways as for instance by very slightly tapering the side walls of the channels 5—5 or by soldering the contiguous faces of the lugs 8 on the complementary bands 6—6. It is preferred, however, to snugly fit the bands in place in order to permit of their removal.

With the simple construction thus disclosed it is possible to use similarly slabbed needles on a multiple needle machine and avoid delays in replacing and ordering the needles. Further the needles may be located close together and thus a series of 85 90 en-chained loops visible on the face of the goods (sewn upside down) may be laid in close parallel rows and in such proximity that an ornamental seam appears as illustrated in my copending application Serial 95 No. 234,009, filed May 11, 1918.

Having thus set forth the nature of the invention, what I claim herein is:—

1. A needle-clamp comprising a block provided with an open ended channel adapted 100 to receive the shank of a needle, removable wall-members at the opposite ends of the channel, a thrust-member for clamping the needle-shank therein and coacting means on the block and wall-members for holding 105 them against displacement relative to the block by the action of the thrust-member.

2. A needle-clamp for securing needles to a needle-bar and having a socket formed therein by a transversely channelled block 110

having lugs on its sides, by embracing bands shaped to encompass said lugs on the blocks, and a thrust member for clamping a series of similar needles each of whose shanks have 5 parallel surfaces.

3. A needle-clamp comprising a block 10 channelled transversely through its bottom face and longitudinally through its opposite sides, a two-part band embracing said block each part having projections fitting into the longitudinal channel in the block, said two-part band forming walls at the opposite ends of the channel in the block, and a thrust member for clamping needles by their 15 shanks within the socket formed by the channelled block and two-part band.

4. A needle-clamp comprising a block provided with a transverse channel and a separate channel extending longitudinally of 20 the block, wall-members at the opposite ends of the transverse channel, a thrust-member for clamping the needle-shanks in the latter channel, and means on the wall-members coacting with one or more walls of the longitudinal channel for holding them against 25 displacement relative to the block by the action of the thrust-member.

5. A needle-clamp having a rectangular 30 socket of uniform depth formed by a block channelled transversely and longitudinally, and by a pair of T-shape channelled members engaging the longitudinal channels in the

block and closing the ends of the transverse channel, and a screw for clamping needle-shanks arranged within the rectangular 35 socket.

6. A needle-bar provided with an axially arranged socket in one end thereof, a needle-clamp having a stud received within said aperture in the needle-bar, a transversely 40 channelled block fixed to said stud, the opposite sides of said channel being parallel, complementary members provided with channels and adapted to close the ends of the channel in the block, projections on the 45 block arranged within the channels of the members for holding the members and block against relative displacement in a direction transverse the needle-bar, and means carried by one of the members in alinement with 50 the channel in the block for clamping a plurality of needles having similar shanks to the lower end of the needle-bar.

7. A needle-clamp for sewing machines provided with an elongated shank-receiving socket having parallel side walls and removable walls at the opposite ends of the socket, and means acting in the direction of the length of the elongated socket for clamping a plurality of needles thereon. 55

In testimony whereof, I have signed my name to this specification.

ALBERT H. DE VOE.
